UNITED STATES PATENT OFFICE.

WILLIAM S. LAWRENCE, OF KALAMAZOO, MICHIGAN.

HARROW-TOOTH HOLDER.

SPECIFICATION forming part of Letters Patent No. 379,018, dated March 6, 1888.

Application filed November 16, 1887. Serial No. 255,290. (No model.)

To all whom it may concern:

Be it known that I, WILLIAM S. LAWRENCE, a citizen of the United States, residing at Kalamazoo, county of Kalamazoo, State of Michigan, have invented a new and useful Harrow-Tooth Holder, of which the following is a specification.

This invention has for its object certain improvements in harrow-tooth holders, substantially as below described and claimed.

In the drawings forming a part of this specification, Figures 1 and 2 are side elevations, with parts in section on the dotted line 1 1 in Fig. 3; Fig. 3, a section on line 2 2 in Fig. 4; Fig. 4, a plan of lettered details in Fig. 2, looking on under side; and Fig. 5, a perspective of a lettered detail, below described.

Referring to the letters marked on the drawings, D D are the crossed beams of an ordinary float-harrow frame. The binding clip or plate A is shaped longitudinally to conform to the curvature of the shank of the tooth B, Fig. 1. It is bent upward and inward at each side, and thence flanged laterally each way, and fits 25 against the under side of the beam. Said flanges e e, Fig. 3, are held by the same bolts, E, which bolt the crossed beams together; but, of course, if employed in harrows in which the beams are not crossed, the bolts would only 30 serve to attach the holder to said beam.

The detachable seat C, Fig. 5, is curved longitudinally on the bottom to fit the concave of the curved portion of the shank of the tooth B, Fig. 1. This seat has a hollowed-out portion or recess, S, on each side. The seat fits 35 against the beam, and the shoulders v of the

inwardly-bent sides of the binder or clip A fit into said recess, and thus when the bolts E are firmly set the seat C is clamped to the beam, and is prevented from lengthwise and lateral 40 displacement.

The shank of the tooth B is adjustably and firmly held clamped to the seat by the clip A, Fig. 1.

The parts C and A are so constructed that 45 they come well below the harrow-beam, and thus hold the shank of the tooth below the beam.

Of course the holder may be shaped to clamp a straight shank of a tooth or share and the 50 seat C may be a shell, as here shown, or solid.

Having thus described my invention, what I claim, and desire to secure, is—

1. The combination, with a harrow tooth and frame, of the seat having the sides hollowed 55 out, the binder having the bent sides with shoulders fitting in the hollow portion of said seat, and the securing-bolts, substantially as set forth.

2. The combination of a harrow beam and 60 tooth, a detachable block constituting a seat for the tooth, a binding-clip having the bent sides engaging the sides of the seat, so as to bind it to the beam, and the securing-bolts, substantially as set forth. 65

In testimony of the foregoing I have hereunto subscribed my name in presence of two witnesses.

WM. S. LAWRENCE.
